PRESSURE SWITCH

Frank McClellan, Detroit, Mich., assignor to Huron Specialty Company, Ann Arbor, Mich., a corporation of Michigan

Application August 10, 1953, Serial No. 373,186

20 Claims. (Cl. 200—86)

The present invention relates to electrical switches and more particularly to pressure-responsive switches.

The present invention is a continuation-in-part of my prior copending application Serial No. 256,567, which has been abandoned.

One object of the present invention is to provide an improved switch which is closed by the application of pressure thereon and automatically returns to open position upon release of pressure.

It is a further object of the present invention to provide a pressure switch characterized by the use of a relatively thick pad or body of compressible and resilient material provided with a plurality of fastening elements formed of electrically conducting material extending completely through the body so as to compress the material thereat and accordingly to locate at least one exposed surface of the fastening element below the plane of the surface of the pad, in conjunction with two conducting layers, such for example as wire mesh, adapted to be in contact with the two surfaces of the pad of resilient material and at least one of which layers is normally out of contact with the fastening elements but adapted to be pressed into engagement with one or more of the fastening elements upon the application of pressure to the pad.

Another object of the present invention is to provide a switch of the above type incorporated in a vehicle warning signal device and arranged to close a signal circuit whenever the vehicle is occupied by an unauthorized person. The switch may thus be carried by the front seat of the vehicle, for example, and arranged to be closed whenever the seat is occupied, thereby closing an electric circuit to a signal device within the automobile, such as the horn relay.

As a feature of the invention, a manual switch is provided in series circuit with the pressure-responsive switch and horn relay, said manual switch being located in a concealed position within the vehicle and normally open except when the vehicle is unattended. Accordingly, only when the manual switch is closed is the pressure-responsive switch operative to energize the horn relay when closed.

It is a further feature of the present invention to provide a switch of the above type including a relatively hard and stiff sheet material extending over the upper surface of the switch device proper, such sheet material being suitable to permit the driving of a wheeled vehicle, such as a grocery cart or automobile, over the switch for actuation thereof.

Other objects and features of the invention will become apparent as the description proceeds, especially when taken in conjunction with the accompanying drawings wherein:

Figure 1 is a top plan view of a preferred form of pressure-responsive switch with parts broken away in order better to illustrate the details of construction thereof.

Figure 2 is a vertical sectional view of the device shown in Figure 1.

2

Figure 3 is a diagrammatic view of the pressure-responsive switch incorporated in a vehicle warning signal circuit.

Figure 4 is an enlarged sectional view through a different embodiment of the present invention.

5 Figure 5 is a fragmentary section through a device in which the pressure switch structure is incorporated in an enclosure including at least an upper surface member of relatively hard stiff sheet material.

10 Figure 6 is a fragmentary section through a device in which the switch structure includes a relatively hard stiff sheet material overlying it, the assembly being enveloped within a sealing enclosure or casing.

15 Referring more particularly to the drawings and especially to Figures 1 and 2 thereof, the pressure-responsive switch there shown is generally indicated by the numeral 10 and comprises a flat generally rectangular body or pad 12 of resilient, compressible dielectric material, such as solid rubber, foam rubber, sponge rubber, plastic or the like. Engaging opposite sides of the body 12 are flat sheets 14 of electrically conducting material which may take the form of metallic screens as shown.

20 Extending through body 12 at a plurality of points are connector elements 16 which may consist of ordinary commercially available staples, having contact parts 18 exposed at opposite surfaces of the body 12. Staples 16 will be formed of metal or other electrically conducting material.

25 As will be seen in Figure 2, contacts 18 of each staple pinch together or compress the portions 20 of body 12 through which the respective staples extend, thereby producing dimples, indentations or recesses in which the contact portions 18 are located, so that the metal sheets 14 engaging the remaining uncompressed portion of said body, are spaced apart a greater distance than, and therefore out of contact with, the contact parts 18 of each staple.

30 Electrical leads 22 and 24 are respectively connected to the metal sheets 14 for connection of the switch in a circuit such as the warning signal circuit illustrated in Figure 3. Enveloping the assembly thus far described is a flexible waterproof enclosure or casing 26 of a dielectric material such as rubber or plastic, having provision of course for the leads 22 and 24 to pass therethrough. 35 As partially shown in Figure 2, the casing 26 may consist of two layers of material secured together at the edges as indicated at 27.

40 The present invention lends itself admirably to the construction of a vapor-proof switch, since the enclosure or casing 26 may be of vapor-proof flexible material, and any openings therein readily sealed.

45 In the normal or uncompressed condition of the body 12, the metal sheets 14 are out of contact with the contact parts 18 of the staples, so that the circuit across the sheets and through the staples is ordinarily open. However, when sufficient pressure is applied forcing sheets 14 inwardly or toward each other, contact is made by the sheets with the opposite contact parts 18 of the staples closing the circuit therethrough. It will be understood that the circuit is closed even though only one of the staples contacts the two metal sheets. However, by employing a large number of connector elements or staples, closing of the circuit is practically assured even though the pressure acting to close the switch acts only on a small portion thereof.

50 It will be noted that the perimeter 13 of the body extends beyond the edges of sheets 14, preventing direct contact of the sheets when pressure is applied thereon. Another method of prevention is to cover the edges of sheets 14 with a suitable non-conducting material such as adhesive tape 15, shown at the upper right corner of Figure 2. This edge binding of the sheets 14 is particularly important where relatively thin bodies are used,

and bodies having a thickness of $\frac{1}{8}$ inch or less have been successfully used.

Although in the normal or uncompressed condition of the switch both contact parts 18 of each staple are out of contact with the adjacent sheet, it will be understood that the circuit through a particular staple will be open so long as at least one of its contact parts is out of contact with the adjacent sheet. This permits a slight variation of construction, as is best illustrated in Figure 4, in which the compressible pad 50 is provided with conducting sheets such for example as foraminous material 52 and 54 at opposite sides thereof. In this case however, fastening elements such for example as the staples 56 or the rivets 58 extend through one of the conducting sheets, and in the illustrated embodiment of the invention through the lower sheet 54. The fastening elements compress the material of the compressible pad as indicated at 60 so that the upper portion of the fastening element is substantially spaced from the uppermost sheet of conducting material 52. Obviously, when pressure is applied over the fastening elements, the adjacent portions of the pad 50 are compressed and permit the upper contact sheet 52 to engage the conducting fastening elements 56 or 58. Obviously, if preferred, the fastening elements could extend through the upper conducting sheet and pad and would leave the lower portions thereof normally spaced from the lower conducting sheet 54. Also, it will be obvious that with this construction instead of providing a continuous conducting sheet at one side of the pad, separate conductors could be applied thereto and directly engaged by the connector elements such as the staples 56 or the rivets 58.

As stated above, it is an object of the invention to provide a vehicle warning system in which my improved pressure-responsive switch is incorporated. Referring now to Figure 3, there is illustrated a warning system circuit which is adapted to be associated with the horn or other signal device of a vehicle to energize the same whenever the vehicle is occupied by an unauthorized person. As illustrated therein, the horn relay 28 is connected in series with the conventional automobile storage battery 30 and the horn button switch 32 by a circuit generally indicated at 34.

Said horn relay is also connected in series with the switch 10 described in detail above, by a second circuit 36. Switch 10 will desirably be placed within the vehicle so that when a person normally occupies the vehicle, the opposite metal sheets 14 of the switch are urged together under pressure making contact with the contact parts 18 of the connector elements or staples to close switch 10, thereby energizing the horn relay 28. Preferably, the switch will be concealed in the front seat of the vehicle so as to be closed by the weight of a person occupying the seat.

In the normal use of a vehicle by authorized personnel, it will of course be desirable to permanently open the circuit to the horn relay through pressure-responsive switch 10, and to this end a manual switch 38 is provided in series circuit with the horn relay and switch 10. Switch 38 will be closed when the vehicle is unattended so that unauthorized entry of the vehicle and resulting closing of switch 10 will result in energization of the horn.

Switch 38 will preferably be located in a concealed position within the vehicle such as in the glove compartment for example, which may be locked to prevent tampering.

Circuits 34 and 36 may be grounded as indicated at 40 and 42.

One of the fields of greatest utility of the present invention is in providing switch structures assembled in the form of mats responsive to the weight of an automobile. Thus, for example, a mat may be provided at the approach to a garage door so that driving the automobile upon the mat will close a circuit to a motor to open

the door. Alternatively, a similar construction may be provided for actuating gates, and a particular field of utility in this connection is in self-service or unattended parking lots wherein the customer drives his car onto the mat which has the effect of opening and holding open the gate, either alone or in conjunction with a suitable coin control mechanism for controlling operation of the gate. For this purpose the basic switch construction illustrated in Figures 1, 2 and 4 is associated with protective means to form a mat as will now be described in conjunction with Figure 5. In this figure there is shown the body of compressible material at 62 having at opposite surfaces thereof conducting sheets 64 and 66 which may conveniently be formed of foraminous material. Fastening elements formed of conducting material are provided at spaced points throughout the area of the body, one of such fastening elements being shown at 68. In this figure the fastening element is shown as of the type normally spaced from both the upper and lower conducting sheets, but may if preferred be applied in accordance with the disclosure of Figure 4 so as to extend through either the upper or lower sheet. The upper and lower sheets 64 and 66 are of course connected to suitable conductors similar to the conductors 22 and 24 shown in Figure 2, so that engagement between one or more of the fastening elements 68 with both of the sheets 64 and 66 completes a circuit. In order to protect the switch construction so far described from destructive action by vehicle wheels and to distribute the wheel pressure weight over a wider pressure area, it is preferably provided with at least an upper protective sheet 70 of a relatively hard and stiff material. Excellent results have been obtained when, in the case of automobile wheels, the upper protective sheet 70 is formed of plywood or a wood product formed of ground wood and plastic, such for example as is presently sold under the trade name Masonite. Alternatively, and for use with wheeled vehicles lighter than an automobile, such as grocery store pushcarts and the like, the upper protective sheet may be formed of metal such for example as aluminum or steel, or of any suitable plastic material. In the preferred construction for use under automobiles, as illustrated in Figure 5, a lower sheet 72 is provided which is similar to the sheet 70 and the edges of the sheets 35 are spaced apart about the structure by a spacer 74 which may for example be formed of a hard incompressible material. Where the spacers 74 are formed of hard incompressible material, the upper protective sheet 70 is somewhat flexible so that under the weight of a vehicle wheel it is moved downwardly to a sufficient extent to insure proper contact between one or more of the fastening elements 68 with both of the screens or other conducting sheets 64 and 66. Alternatively, the spacer strips 74 may be formed of a compressible material such for example as rubber, in which case flexibility of the relatively hard and stiff protecting sheet 70 is not an essential requirement. However, in the dimensions in which the protective sheet is normally required it is inherently flexible to a degree to permit operation of the switch. The operation of the switch does not depend alone upon the flexibility of the protective cover sheet 70 but upon the compressibility and resilience of the body of material 62 between the two conducting sheets 64 and 66.

In order that the complete mat illustrated in Figure 5 comprising the upper protective sheet 70, the lower sheet 72 and the spacer strips 74, may be used simply by placing it on the ground or other support surface at the required point it is preferred to bevel the appropriate edges of the mat as indicated at 76.

Preferably, the mat is covered with a wearing layer 78 of suitable material such for example as rubber or other durable material.

Referring now to Figure 6 there is shown another embodiment of the present invention. In this case the switch assembly comprises a mat structure designed pri-

marily for use in controlling door movement in markets or the like. The construction is designed to provide a waterproof enclosure for the operating parts of the mechanism. As seen at the left of the figure, the mat may comprise a rubber mat body 80 having at least one edge tapered as indicated at 82 and having a recess 84 extending upwardly thereinto from the bottom thereof. The recess 84 is adapted to be closed by a closure element 86 which may conveniently also be formed of rubber and sealed to the mat body 80 as indicated at 88, so as to provide a water-tight enclosure. Located within the recess 84 is the switch device comprising the flat body 90 of resilient compressible material such for example as rubber, having associated therewith a lower screen or other conducting sheet 92, an upper conducting screen or conducting sheet 94, the resilient compressible body 90 being provided with elements 96 extending therethrough and adapted to form contacts with either or both of the sheets 92 or 94. As illustrated, the elements 96 are shown as staples extending through the upper conducting sheet 94 and having downwardly exposed contact portions received in recesses or dimples beneath the lower surface of the resilient compressible body 90. It will be understood that these elements may be of the types fully described in the foregoing.

Located in the recess 84 directly above the sandwich comprising the upper and lower conducting sheets and the interposed compressible resilient body is a hard stiff plate 98 which may be formed of metal, plastic or other suitable material. Preferably, a similar plate 100 is provided at the bottom of the recess directly above the closure element 86, although the lower hard stiff plate 100 may if desired be omitted. If the lower hard stiff plate 100 is provided, its edges are spaced from the edges of the upper plate 98 by a spacer 101 of suitable dielectric material.

It will be observed that pressure applied to the upper tread surface of the mat body 80 is transmitted downwardly producing compression of the resilient compressible body and causing the conductive layers 92 and 94 to approach, thereby bringing about contact between one or more of the elements 96 with both of the conducting sheets.

As indicated at the right of Figure 6, when a hard stiff sheet such as shown at 102 is provided and is formed of conducting material, it will be unnecessary to employ the conducting sheet 94 since the sheet 102 will serve to distribute pressure and also act as a contact element of the switch. In this case a screen may if desired, be provided at the bottom of the resilient compressible body 90 or such screen may be omitted if a lower metal sheet such as illustrated at 104 is provided.

This construction is particularly useful in exposed locations since it is waterproof. The mat body may be formed of a suitable hard wearing rubber capable of withstanding substantial wear over extended periods. The use of the upper hard stiff plate not only improves the wearing properties of the mat assembly, but also improves the feel since it prevents substantial local depression by weights applied thereto. It has the additional function of distributing the weight load over a substantial area so that under anticipated loads it is effective to close a number of contacts simultaneously.

It will be understood that the pressure-responsive switch 10 has a wide variety of other possible uses. For example, the switch may be incorporated in a floor mat at the entrance of a house to ring a bell or buzzer or to turn on a light, or such a mat may be positioned at the entrance or exit of a store for opening and holding open the door, or for preventing it from being opened, in response to pressure upon the switch provided by the weight of a person standing upon it; or similarly, such a mat may be used to switch on a spotlight, or to illuminate and direct attention to a fixed message of warning or of instructions, or to set off a burglar alarm,

or the like. Also, the switch may be incorporated in a soft pad of suitable shape and dimensions for attaching to the advancing edge of a sliding or descending door or gate, or to a vehicle or machine, for use as a trigger to stop the movement of the mechanism in response to pressure on the pad as by contact with a person or other object. Also, the switch may be located in a floor mat adjacent to an electrically operated tool, so that whenever the workman stands on the mat in working position the energizing circuit of the tool will automatically be closed through the switch to actuate the tool.

The switch does not have to be flat in form or rectangular in shape, as shown in the drawing, but may be of any form and shape—such as cylindrical or tubular or convex—and of any dimensions that may be necessary or convenient for the fulfillment of its intended purpose.

Obviously, of course, a single mat may incorporate a plurality of electrically independent conducting sheets at one or both sides of the compressible body for connection into separate circuits.

The drawings and the foregoing specification constitute a description of the improved pressure switch in such full, clear, concise and exact terms as to enable any person skilled in the art to practice the invention, the scope of which is indicated by the appended claims.

What I claim as my invention is:

1. A pressure switch comprising a body of compressible resilient dielectric material, a metallic electrically conducting and compressing element extending completely through said body and having a contact portion on at least one side of said body arranged to compress and to displace the localized adjacent surface portion of said body inwardly so as to thereby position said contact portion beneath the general surface of said body, a conductor engaging the general surface of said body and normally spaced from said contact portion of said element but engageable therewith when pressure is applied to said conductor over said contact portion.
2. A switch as defined in claim 1 in which said body comprises a flat pad.
3. A switch as defined in claim 1 in which said conducting and compressing element comprises a staple.
4. A switch as defined in claim 1 in which said conducting and compressing element comprises a rivet.
5. A switch as defined in claim 1 in which a plurality of conducting and compressing elements are provided, and said conductor comprises a sheet extending across all of said elements.
6. A switch as defined in claim 1 in which a plurality of conducting and compressing elements are provided, and said conductor comprises a sheet of foraminous material extending across all of said elements.
7. A pressure switch comprising a pad of compressible resilient di-electric material, two electrically conducting members engaging opposite surfaces of said pad, an electrically conductive connector element extending through said pad between said members and having a contact portion at one side of said pad extending across a portion of the surface of said pad and disposed to form an indentation in the surface of said pad and to space said contact portion from the adjacent one of said members.
8. A switch as defined in claim 7 in which said conducting members are in the form of sheets.
9. A pressure switch comprising a pad of compressible resilient di-electric material, two electrically conducting members engaging opposite surfaces of said pad, an electrically conductive connector element having a first portion connected to one of said members and a second portion at the opposite side of said pad from said first portion engaging the surface of said pad and compressing the portion of the pad therebeneath to form an indentation in the surface of the pad and to space said second portion from the adjacent conducting member.

10. A switch as defined in claim 9 in which said connector element is a staple.
11. A switch as defined in claim 9 in which said connector element is a rivet.
12. A switch as defined in claim 9 in which said conducting members are metal screens.
13. A switch as defined in claim 9 in which said conducting members are metal screens and said connector element is a staple.
14. A switch as defined in claim 9 in which said conducting members are metal screens and said connector element is a rivet.
15. A pressure switch comprising a pad of compressible resilient dielectric material, two electrically conducting members engaging opposite surfaces of said pad, an electrically conductive connector element extending completely through said pad and having contact portions at opposite sides of said pad spaced apart a distance substantially less than the uncompressed thickness of said pad to form indentations in opposite surfaces of said pad and to space said contact portions inwardly from said conducting members.
16. A switch as defined in claim 15 in which said connector element is a staple.
17. A switch as defined in claim 15 in which said connector element is a rivet.
18. A switch as defined in claim 15 in which said conducting members are metal screens.
19. A switch as defined in claim 18 in which said connector element is a staple.
20. A switch as defined in claim 18 in which said connector element is a rivet.
